UNITED STATES PATENT OFFICE.

GEORGE H. GIBSON, OF MONTCLAIR, NEW JERSEY, ASSIGNOR TO COCHRANE CORPORATION, OF PHILADELPHIA, PENNSYLVANIA, A CORPORATION OF PENNSYLVANIA.

HEAT EXCHANGER.

Original application filed April 13, 1921, Serial No. 461,075. Divided and this application filed December 19, 1921. Serial No. 523,548.

To all whom it may concern:

Be it known that I, GEORGE H. GIBSON, a citizen of the United States, and resident of Montclair, in the county of Essex and 5 State of New Jersey, have invented certain new and useful Improvements in Heat Exchangers, of which the following is a specification.

The object of my present invention is to 10 provide simple and effective apparatus for effecting a transfer of heat from liquid at one temperature to liquid at a lower temperature by vaporizing a portion of the liquid at the higher temperature and thus 15 abstracting heat from the unvaporized portion of the liquid, and condensing the vapor thus generated by the colder liquid which thereby absorbs the heat liberated by the condensation of the vapor.

20 The various features of novelty which characterize my invention are pointed out with particularity in the claims annexed to and forming a part of this specification. For a better understanding of the invention, 25 however, and its advantages, and specific objects, attained with its use, reference should be had to the accompanying drawings in which I have illustrated a preferred embodiment of my invention and one of the 30 uses to which it may be put.

Of the drawings:

Fig. 1 is an elevation partly in section of my improved form of heat exchanger; and

35 Fig. 2 is a diagrammatic representation of a water purifying and deaerating plant in which the heat exchanger may be employed.

40 My improved heat exchanger in the form shown in Fig. 1 is what I may call an open heat exchanger. It comprises a chamber A having its lower portion divided into two water receiving compartments A' and A² by a partition B which terminates below 45 the top of the chamber so that the upper portions of the compartments A' and A² are in free communication with one another over the top of the partition B. A³ represents a liquid outlet from the bottom of compartment A', and A⁴ is a liquid outlet from the bottom of the compartment A². Relatively hot liquid is introduced into the 50 top of the compartment A' by a supply pipe C, and relatively cool liquid is introduced

into the top of the compartment A² by a 55 supply pipe F.

The apparatus is operated so that the pressure of the liquid in the pipe C is above the pressure in the vapor space in the heat exchanger, and is at such temperature that 60 when the pressure of the liquid is reduced as it passes into the heat exchanger from the pipe C, a portion of the liquid will be converted into vapor, and the temperature of the uncondensed portion of the liquid supplied by the pipe C will be correspondingly 65 reduced. In the construction shown provisions are made for passing the water discharged from the conduit C through the vapor space in the compartment A' in 70 finely divided form. For this purpose the discharge from the conduit C is through a spray head C² and on to a set of trays or baffles D, which may be like those used in 75 an ordinary water heater and over which the water flows in film-like and broken streams.

In Fig. 1 the supply of water to the heat exchanger through the conduit C is regulated to maintain an approximately constant water level in the compartment A', by means of a valve C' in the pipe C and a float E rising and falling with the water level in the compartment A' and controlling the valve C'.

80 To facilitate the condensation of the vapor generated in the compartment A' by the water introduced to the compartment A² through the conduit F, I preferably pass the water discharged by the conduit F 90 through the vapor space in the compartment A² in a finely divided form. For this purpose I provide, in the construction illustrated, an overflow trough F' receiving the discharge from the conduit F and from 95 which the liquid supplied to it overflows on to a set of water spreading trays or baffles DA.

To prevent the heat exchanger from becoming air bound, an air outlet A⁵ should 100 be provided and when it is desired to operate with a pressure in the vapor space of the heat exchanger lower than atmospheric the air outlet A⁵ should be connected to a suitable air exhauster which may be, as shown, a steam jet ejector G, G' representing the steam supply connection to the ejector and G² the ejector discharge outlet. 105

The necessity for an air outlet is appreciably marked because the conditions of operation tend to liberate in the exchanger air dissolved or entrained in the water passing 5 into the exchanger.

The heat exchanger shown in Fig. 1 is relatively simple and inexpensive in construction and highly efficient and is adapted for many different uses. One of these uses, 10 illustrated by way of example in Fig. 2, is the heating of boiler feed water or the like, and freeing the water from air or other contained gases in case, as when the water is supplied to an economizer, it is desirable 15 in the deaeration process to heat the water to a temperature appreciably above that at which it is desirable to pass the heated and treated water away from the apparatus.

In the water deaerating and heating apparatus shown in Fig. 2, raw water is supplied to the apparatus through the pipe F which discharges into the compartment A² of the heat exchanger A. This water, and the water of condensation added to it in 20 the heat exchanger passes through the outlet A⁴ to the inlet of a pump H from which it is passed through the pipe H' to the water inlet of the heater I which, as diagrammatically shown is in the form of an 25 open feed water heater mounted above and discharging into a closed settling tank IA. The usual water spreading baffles DB are provided in the heater I. Live or exhaust steam is supplied to the heater I in the 30 usual manner through a conduit K and separator I². The supply of water to the apparatus through the conduit F is controlled by the valve F⁵ which is actuated by a float EA in the tank IA so as to 35 maintain an approximately constant water level in the tank IA. The outlet G³ from the air ejector G discharges into the heater I. The air carried into the heater through 40 the conduit G³, and the air liberated from the water and steam passed into the heater I through the pipes H' and K respectively, escapes from the heater I into the settling tank IA, and passes out of the latter through the air outlet I¹⁰ which 45 opens from the tank IA above the water level therein. To recover the vapor and heat carried by it passing out of the tank IA through the air outlet I¹⁰, the latter in the form shown discharges into a gleaner 50 or condenser J. The latter comprises a jacket surrounding the raw water supply pipe F. Water of condensation formed in the jacket J drips through the outlet J' into the water sealed return connection I⁵ 55 to the heater I, while the air entering the jacket escapes to the atmosphere through the outlet J'.

In the contemplated mode of operation 60 of the apparatus shown in Fig. 2, the raw water supplied to the heat exchanger A

through the pipe F, normally at a temperature of 50 to 70° or so, is heated in the heat exchanger to the desired temperature which is that of water vapor at the pressure which the apparatus is operated to maintain in 70 the vapor space of the heat exchanger. This temperature in ordinary practice may be something like 130 or 140°. The water supplied to the compartment A² by the pipe F and the water of condensation formed in the compartment A² is passed by the pump H into the heater I where it is heated to the desired temperature of 212° or a little above to facilitate the deaeration of 75 the water. From the tank IA the heated water passes through the funnel I¹⁵ and the water outlet I¹⁶ to the pipe C and thence into the compartment A' of the heat exchanger. The water passes through the pipe C into the spray head C² at a pressure equal to or ordinarily a trifle above that of the atmosphere. In passing through the spray head C² the pressure of the water is reduced to that maintained in the vapor space of the heat exchanger with a consequent generation of vapor, and a reduction in temperature of the vapor and of the uncondensed water to the temperature corresponding to the vapor pressure in the heat 80 exchanger. The mechanical dispersion of the water as it leaves the spray head due not only to the spray discharge but to the conversion of a portion of the water into vapor and the flow of the water over the baffles D facilitates the liberation of air 85 dissolved in the water and mechanically held in the water supplied to the heat exchanger through the conduit C. A considerable portion of the air dissolved in or entrained by the water supplied through the conduit F is also liberated in the heat exchanger A as a result of the heating of this water and its flow through the vapor space of the heat exchanger in a finely divided form. The air thus liberated is 90 withdrawn by the ejector G, and is passed into the heater I from which as already explained, it eventually escapes through the tank IA, outlet pipe I¹⁰ and gleaner J into 95 the atmosphere. 100

While the use of a heat exchanger in connection with a water heater in a water heating and deaerating plant or the like shown in Fig. 1 is novel with me, it is not claimed herein but is claimed in my co-pending application, Serial No. 461,075, filed April 13, 1921, of which the present application is a division. It will be apparent to those skilled in the art that changes may be made in the form of my invention without departing from the spirit of my invention as set forth in the appended claims, and that certain features of my invention may sometimes be used to advantage without a corresponding use of other features. 110 115 120 125 130

Having now described my invention, what I claim as new and desire to secure by Letters Patent, is:

1. Means for transferring heat from one liquid to another comprising a single closed chamber, a partition therein dividing the lower portion of each chamber into two separate water compartments, each in free communication at its upper end with the upper end of the other, means for passing the hotter liquid into one of said compartments at a temperature above that of saturated vapor of the liquid at the vapor pressure prevailing in said chamber, means for passing the colder liquid into the other compartment, and separate means for withdrawing water from the two compartments.
2. A heat exchanger comprising a closed chamber divided internally into two separate water receiving compartments in communication with one another at their upper ends, a hot liquid inlet opening to the upper portion of one of said compartments, a cool liquid inlet opening to the upper portion of the other compartment, water spreading devices in the upper portion of each compartment for causing the water admitted to each compartment to pass through the upper portion thereof in a finely divided condition, and separate water outlets from the two compartments.
3. A heat exchanger comprising a closed chamber divided internally into two separate water receiving compartments in communication with one another at their upper ends, a hot liquid inlet opening to the upper portion of one of said compartments, a cool liquid inlet opening to the upper portion of the other compartment, water spreading devices in the upper portion of each compartment for causing the water admitted to each compartment to pass through the upper portion thereof in a finely divided condition, and separate water outlets from the two compartments.

Signed in Philadelphia, in the county of Philadelphia and State of Pennsylvania, this sixteenth day of December A. D. 1921.

GEORGE H. GIBSON.
